UNITED STATES PATENT OFFICE.

GEORGE WASHINGTON, OF BROOKLYN, NEW YORK.

HYDROCARBON INCANDESCENT LAMP.

SPECIFICATION forming part of Letters Patent No. 760,670, dated May 24, 1904.

Application filed December 17, 1897. Serial No. 662,317. (No model.)

To all whom it may concern:

Be it known that I, GEORGE WASHINGTON, of Brooklyn, in the county of Kings and State of New York, have invented certain new and useful Improvements in Hydrocarbon Incandescent Lamps; and I do hereby declare the following to be a full, clear, and exact description of the invention, such as will enable others skilled in the art to which it appertains to make and use the same.

My invention relates to an improvement in lamps; and it consists in an incandescent burner, a commingling-chamber connected therewith, and a vaporizing-tube having one or more coils embracing the mantle, the said vaporizing-tube discharging into the commingling-chamber.

My invention further consists in an incandescent burner provided at one side with a commingling-chamber and a vaporizing-tube having one or more coils which encircle the mantle.

My invention further consists in the parts and combinations of parts, as will be more fully described, and pointed out in the claims.

The accompanying drawing is a view in elevation, partly in section, of my improved lamp.

A represents a burner cylindrical in shape and provided near its lower end with a stud *a*, having a lateral slot therein for the reception of the vaporizing-tube *B*. This tube *B* is attached at its lower end to the coupling *B*³, which can be attached to a wall-bracket or to a portable lamp and is provided with a passage-way for the free passage of oil to the commingling-tube *B*, which latter is connected at its lower end to the coupling. The burner *A* is also carried by the coupling *B*³, and the commingling tube or chamber *E* thereof is located in a position to receive the vapor discharged from the vaporizing-tube. The upper portion of the tube *B* is bent at right angles to the vertical stem of the tube and formed into one or more coils *B*², which latter are designed to rest outside of and in close proximity to the mantle. This coil or coils *B*² normally rests in a plane between the top of the mantle and the burner; but from experience I have found that probably the best

results are attained by locating the coils slightly above the burner, so as to come within the field of the flame. The discharging end of the vaporizing-tube is provided with a downwardly-projecting ejector-nozzle *c*, 55 which latter passes through an opening in cap *d* of the commingling-chamber *E* and discharges the vapor directly onto the latter. This commingling-chamber is preferably in the form of a cylinder approximately the 60 length of the burner *A* and in open communication at its lower end with the burner.

The burner and its attached commingling-chamber and vaporizing-tube are removably supported on or carried by the coupling *B*³, 65 and the tube and burner are held against displacement by the set-screw *f*, carried in the stud *a* and engaging the tube, the stud being fixed to the burner and slotted, as described, to receive the tube *B*.

Secured to the burner, near the center thereof, is the upwardly-projecting mantle-support *F*. The mantle *J*, which is suspended from this support, rests within the coil or coils of the vaporizing-tube. Hence when the mantle 75 is heated by the burning vapor and air the coil or coils become heated and rapidly vaporize the oil and retains the vapor in a heated condition until it is discharged into the commingling-chamber. This commingling-chamber *E* is provided with an opening *e* for the ingress of air, and the latter is drawn into the chamber by the injector action of the vapor-jet and is thoroughly commingled with the vapor. The discharge of vapor from the vaporizing-tube into the commingling-chamber is regulated and controlled by the needle-valve *G*, which latter passes upwardly through a stuffing-box *g* in the lower end of the chamber and rests with its tapering end within the outlet-opening of the vaporizing-tube. The valve can be screw-threaded for moving it longitudinally or it can be actuated by a lever or other suitable device.

The mantle-support *F* is attached centrally 95 to the burner and operates to support the mantle in position over the burner and within the coil or coils of the vaporizing-tube.

I is the starting-cup secured to the burner embracing or surrounding the burner. This 100

cup is designed to contain sufficient alcohol or oil which when ignited produces sufficient heat to vaporize the oil in the vaporizing-tube adjacent thereto. The vapor thus generated 5 rises in the tube and passing around the coils is discharged from the ejector-nozzle *c* downwardly into the commingling-chamber, and acting as an injector draws in air from the outside through opening *e*. The air thus 10 drawn in mixes with the vapor and passes into the burner, and as it issues from the latter is ignited by the burning alcohol in the starting-cup.

The oil can be fed to the vaporizer-tube by 15 gravity or air or other pressure, and the intensity of the light can be regulated by increasing or lessening the supply of vapor to the burner. The light may be extinguished by closing the opening in the ejector-nozzle 20 or by the valve *G* or it can be extinguished by cutting off the supply of oil by turning a cock located in the oil-supply pipe.

Having fully described my invention, what I claim as new, and desire to secure by Letters 25 Patent, is—

1. In a hydrocarbon incandescent lamp, the combination with a burner, and a commingling-chamber approximately parallel with the burner and discharging into the latter, of 30 a coupling having means for its attachment to a suitable base or support and supporting the burner and its commingling-chamber and provided with an oil-duct, and a vaporizing-tube leading from the egress end of said duct to 35 the commingling-chamber and located within the heating zone of the burner.

2. In a hydrocarbon incandescent lamp, the combination with a burner, and a commingling-chamber approximately parallel with 40 the burner and discharging into the latter, of a coupling having means for its attachment to a suitable base or support and supporting the burner and its commingling-chamber, and provided with an oil-duct, and a vaporizing-tube 45 leading from the egress end of said duct to the commingling-chamber and provided in-

termediate its ends with a coiled section the latter being located within the heating zone of the burner.

3. In a hydrocarbon incandescent lamp, 50 the combination with a burner, a commingling-chamber communicating therewith and a starting-cup adjacent to the burner, of a vaporizing-tube comprising two straight sections, both of which are within the heating 55 zone of the mantle, one of said straight sections discharging the vapor into the commingling-chamber and an intermediate coiled section, the coiled section being located over the starting-cup and burner, and shaped to 60 receive and surround the mantle, and a mantle-support carried by the burner, substantially as set forth.

4. In a hydrocarbon incandescent lamp, 65 the combination with a removable vaporizing-tube comprising a straight section and a coil at right angles to said straight section the said coil adapted to surround an incandescent mantle, of an incandescent burner a commingling-chamber located in line with the vapor- 70 discharge orifice in the vaporizing-tube and a needle-valve in the commingling-chamber for closing such orifice.

5. In a hydrocarbon incandescent lamp, 75 the combination with a burner, and a commingling-tube in communication therewith, of a vaporizer-tube comprising two straight members and an intermediate coil, both straight members and the coil being within the heating zone of the burner, and one of said 80 straight members of the vaporizer-tube discharging into the commingling-chamber and a bracket supporting said burner and having an oil-supply duct leading to the other straight member of the vaporizing-tube. 85

In testimony whereof I have signed this specification in the presence of two subscribing witnesses.

G. WASHINGTON.
